United States Patent Office

Des. 184,632
Patented Mar. 17, 1959

184,632

CHAIR

William W. McTyeire, Jr., Birmingham, Ala.

Application October 13, 1958, Serial No. 52,963

Term of patent 14 years

(Cl. D15—1)

The single figure of the drawing is a front perspective view of a chair showing my new design.

What I claim is:

The ornamental design for a chair, as shown.
